UNITED STATES PATENT OFFICE.

JOSEPH E. DIXON, OF SAN FRANCISCO, CALIFORNIA.

DESIGN FOR A MEDAL.

43,498.

Specification for Design.

Patented Feb. 4, 1913.

Application filed October 18, 1912. Serial No. 726,573. Term of patent 7 years.

To all whom it may concern:

Be it known that I, JOSEPH E. DIXON, a citizen of the United States, residing at San Francisco, in the county of San Francisco and State of California, have invented a new, original, and ornamental Design for Medals, of which the following is a specification, reference being had to the accompanying drawing, forming part thereof.

In the drawing, Figure 1 is a representation of the obverse of the medal, and Fig. 2 is a representation of the reverse of the medal.

The obverse of the medal, as shown in Fig. 1, bears a relief map of the port of Portland, Oregon, showing portions of the Columbia and Willamette rivers at their confluence, the Pacific ocean at the mouth

of the Columbia river, and portions of the territory adjacent to these rivers together with a conventional representation of a city situated on the opposite banks of the Willamette. The reverse of the medal, as shown in Fig. 2, bears in relief the representation of a mountain peak, with a lake and spurs of mountains in the foreground.

I claim:

The ornamental design for a medal herein shown and described.

In testimony whereof I affix my signature in the presence of two subscribing witnesses.

JOSEPH E. DIXON.

Witnesses:

ROBERT TUCKER,
BERYL CORNELL.
